UNITED STATES PATENT OFFICE

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

MOTOR CONTROL APPARATUS

Application filed July 5, 1929, Serial No. 376,046. Renewed May 12, 1931.

My invention relates to motor control apparatus.

I will describe two forms of apparatus embodying my invention, and will then point out the novel features thereof in claims.

In the accompanying drawings, Fig. 1 is a diagrammatic view showing one form of apparatus embodying my invention applied to a control of a motor for operating a railway switch. Fig. 2 is a similar view showing a modified form of a portion of the apparatus illustrated in Fig. 1, and also embodying my invention.

Similar reference characters refer to similar parts in both views.

Referring first to Fig. 1, the reference character M designates an electric motor comprising an armature 1 and a field winding 2. As here shown, the motor M controls a rail-way switch A through the medium of suitable operating mechanism forming no part of my invention and therefore not shown in the drawings, but it will be readily understood that the motor M might be used to control any other suitable form of apparatus.

Associated with the motor M is a motor controller C comprising two contactors E and F. The contactor E, in the form here shown, comprises a magnetizable armature 38 pivoted at 38^a and controlled by a winding 36. The armature 38 is operatively connected with two contacts 4 and 9. When winding 36 is de-energized, the armature 38 occupies the position in which it is illustrated in the drawings and the contacts 4 and 9 are open. When winding 36 is energized, however, the armature 38 is rotated in a clockwise direction to a position in which the contacts 4 and 9 are closed. In similar manner, the contactor F comprises a magnetizable armature 39 pivoted at 39^a and controlled by a winding 29. The armature 39 is operatively connected with two contacts 16 and 19. When winding 29 is de-energized the armature 39 occupies the position shown and contacts 16 and 19 are open; but, when winding 29 is energized armature 39 is rotated in a counter-clockwise direction to a position in which the contacts 16 and 19 are closed. A push rod 40 is slidably mounted in holes formed in two fixed

abutments 41 and 42, and is arranged to coact with the armatures 38 and 39 of the contactors E and F in such manner that one armature cannot be moved to the position in which its associated contacts are closed unless the other 55 armature occupies the position in which its associated contacts are open, thus insuring that the contacts of both contactors cannot be simultaneously closed.

The motor controller C also comprises two thermo-sensitive relays S and T. The thermo-sensitive relay S comprises a thermo-sensitive device which changes its shape in response to changes in its temperature, and a heating element 21 for heating the device. 60 As here shown, the thermo-sensitive device is a bi-metallic strip 27 arranged in such manner that the free end of the strip will deflect upwardly when the heating element 21 is supplied with current, the magnitude of 65 which exceeds the magnitude of the normal operating current for motor M. The bi-metallic strip 27 operates a contact 27—27^a which is normally closed but which becomes opened when the strip 27 is deflected. Associated with the strip 27 is a pivoted latch 43, 70 provided with a notch 43^a, and biased to the position shown by means of a spring 44. The upper end of the latch 43 is connected by a wire 46 or other suitable link with the upper 75 end of the armature 38 of contactor E. The parts or relay S are so arranged and proportioned that when the strip 27 is deflected upwardly, the end of the strip 27 will be engaged by the latch 43 at the notch 43^a and held 80 in the deflected position until winding 36 of contactor E is subsequently energized, at which time the movement of the armature 38 of contactor E to its energized position swings the link in a clockwise direction against the 85 bias of the spring 44 and releases the strip 27. The thermo-sensitive relay T is similar to the thermo-sensitive relay S and comprises a bi-metallic strip 34 arranged to deflect upwardly 90 when a heating element 11 associated with the strip is supplied with current the magnitude of which is greater than the magnitude of the normal operating current for motor M. The strip 34 operates a contact 34—34^a, 95 and co-operates with a pivoted latch 49, which 100

is provided with a notch 49^a, and which is biased to the position shown by a spring 47. The upper end of the latch 49 is connected by a wire 50 or other suitable link with the upper end of the armature 39 of contactor F, and the parts are so arranged and so proportioned that when the bi-metallic strip is deflected upwardly the end of the strip will enter the notch 49^a and will be held in the deflected position until winding 29 of contactor F is energized to rotate the latch to a position in which the latch is out of engagement with the bi-metallic strip 34.

The motor controller C may be controlled 15 in any suitable manner. As here shown it is controlled by a circuit controller D operatively connected with the switch A, and by a polarized relay R. The circuit controller D comprises a contact arm 31 which coacts 20 with two contact segments 31^a and 31^b. The parts of the circuit controller D are so proportioned that the arm 31 will engage the segment 31^a to close the contact 31—31^a at all times except when the switch occupies its extreme normal position in which it is illustrated in the drawing, and that the arm 31 will engage the segment 31^b to close contact 25 31—31^b at all times except when the switch A occupies its extreme reverse position. The 30 polarized relay R, in turn, may be controlled in any suitable manner, as by pole-changing contacts on a switch lever located in the train dispatcher's office.

As shown in the drawings, switch A occupies its normal position so that contact 31—31^b of circuit controller D is closed and contact 31—31^a is open. Polarized relay R is energized in its normal direction. Contactors E and F are both de-energized and contacts 9 and 4 of contactor E and contacts 16 and 19 of contactor F are therefore open. Motor M is de-energized. Bi-metallic strips 27 and 34 of thermal relays S and T both occupy their normal positions in which contacts 45 27—27^a and 34—34^a are closed. I will now assume that the train dispatcher wishes to reverse switch A. To do this he reverses the polarity of the current supplied to relay R so that relay R becomes energized in the reverse direction to open normal contact 50 25—25^a and close reverse contact 25—25^b. Current is then supplied to winding 36 of contactor E from the terminals B and X of a suitable source of current not shown in the drawings over a circuit which passes from terminal B of the source through wire 23, front contact 24 of relay R, wire 24^a, reverse contact 25—25^b of relay R, wire 33, contact 34—34^a of thermo-sensitive relay T, wire 35, winding 36 of contactor E, wire 37, contact 31—31^b of circuit controller D and wire 32 to terminal X. As a result, winding 36 of contactor E becomes energized, and armature 38 is moved to the position in which contacts 9 and 4 of the contactor are closed. When

these contacts are closed, a circuit for motor M is completed, and current flows from terminal B of the source through wire 3, contact 4 of contactor E, wires 5 and 6, armature 1 of motor M, wires 7 and 8, contact 9 of contactor E, wire 10, heating element 11 of relay T, wires 12 and 13, field winding 2 of motor M, and wire 14 to terminal X. Motor M therefore operates to move switch A from its normal to its reverse position. When the switch reaches its full reverse position, contact 75 31—31^b of circuit controller D opens, thereby interrupting the circuit previously traced for winding 36 of contactor E, so that contactor E becomes de-energized and opens its contacts 4 and 9. When contacts 4 and 9 of contactor E are opened, the circuit just traced for motor M is interrupted and the motor stops. All parts are then de-energized.

If, after the switch has reached its full reverse position, the train dispatcher wishes to restore the switch to its normal position, he restores relay R to its normal position, in which it is illustrated in the drawings. Contact 31—31^a of circuit controller D is now 80 closed, and current therefore flows from terminal B of the source through wire 23, neutral contact 24 of relay R, wire 24^a, normal contact 25—25^a of relay R, wire 26, contact 27—27^a of relay S, wire 28, winding 29 of 85 contactor F, wire 30, contact 31—31^a of circuit controller D, and wire 32 to battery X. Contactor F therefore becomes energized and closes its contacts 16 and 19. When these contacts are closed, a circuit is completed for 90 motor M from terminal B of the source through wire 15, contact 16 of contactor F, wires 17 and 7, armature 1 of motor M, wires 6 and 18, contact 19 of contactor F, wire 20, heating element 21 of relay S, wires 22 and 100 13, field winding 2 of motor M, and wire 14 to terminal X. Motor M then operates to restore switch A to the normal position. When the switch reaches its full normal position, contact 31—31^a of circuit controller D opens 105 and de-energizes contactor F. When contactor F becomes de-energized, the contactor opens its contacts and interrupts the circuit just traced for motor M so that the motor stops, and the parts are then restored to the 110 positions in which they are illustrated in the drawings.

If the motor current rises above the normal value for any reason when switch A is being moved from one extreme position to the other, the motor will be automatically de-energized, so that damage to the motor is prevented. For example, I will assume that the motor current rises above the normal value when switch A is being moved from its normal to its reverse position due to the movement of the switch being arrested by some obstruction before the switch reaches its full reverse position. As pointed out hereinbefore, when switch A is being moved from its 115

normal to its reverse position, motor M is energized over the contacts 9 and 4 of contactor E, and heating element 11 of relay T is included in the motor circuit. It will be apparent, therefore, that when the motor current rises above the normal value under the above conditions, bi-metallic strip 34 of relay T becomes heated, and the end of the strip deflects upwardly and is engaged to the latch 49. The circuit for contactor E is then opened at contact 34-34^a of relay T so that contactor E becomes de-energized and thus de-energizes motor M.

After motor M has been de-energized in this manner, the motor cannot again be energized in the direction to move switch A toward its reverse position until strip 34 is released and returns to its normal position in which contact 34-34^a is closed. If the train dispatcher now energizes relay R in the normal direction so that its contact 25-25^a becomes closed, contactor F will become energized and will rotate latch 49 out of engagement with strip 34. If strip 34 has had time to cool before this is done, the strip will immediately return to its normal position and close contact 34-34^a. If bi-metallic strip 34 is still heated, however, when this is done, latch 49 may reengage the strip 34, and the strip cannot then be released unless latch 49 is manually rotated out of engagement with the strip, because when contactor F becomes energized, motor M becomes energized and moves switch A toward its initial or normal position, and when switch A reaches its normal position, contactor F automatically becomes de-energized at contact 31-31^a of circuit controller D. Latch 49 then returns to the normal position to which it is biased by the spring 47, and if strip 34 is still heated, the latch will re-engage the strip and will hold the strip in its deflected position until the latch is manually operated to release the strip.

In similar manner, if the motor current rises above the normal value when switch A is being moved from its reverse to its normal position, strip 27 of relay S will become deflected and will de-energize contactor F, thereby de-energizing motor M. When strip 27 becomes deflected, latch 43 engages the strip and holds the strip in its deflected position. Motor M cannot then again be energized in the direction to move switch A toward its normal position until strip 27 is released and returns to its normal position in which contact 27-27^a is closed. If relay R is energized in the reverse direction so that its contact 25-25^b becomes closed, contactor E will become energized and will rotate latch 43 out of engagement with strip 27. If strip 27 has cooled before this is done, the strip will immediately return to its normal position and close contact 27-27^a. If bimetallic strip 27 is still heated, however, when this is

done, latch 43 may re-engage the strip 27 and the strip cannot then be released unless latch 43 is manually rotated out of engagement with the strip.

Referring now to the modified form of apparatus illustrated in Fig. 2, I have here shown, associated with bimetallic strip 34 of thermo-sensitive relay T a latch 51 having two notches 51^a and 51^b. The latch 51 is pivoted at 51^c and is biased to the position shown by the spring 47. The notch 51^a in the latch 51 coacts with the bimetallic strip 34 in the same manner as the notch 49^a in the latch 49 coacts with the strip 34 in Fig. 1. The notch 51^b coacts with a lock rod 53 pivotally attached near its upper end to a pivoted arm 54 which is biased to an upper position by a spring 55. The lower end of the lock rod 53 is provided with an elongated slot 53^a which receives a pin 48 attached to the bimetallic strip 34. The upper portion of the latch 51 is connected with the armature 39 of contactor F by the wire 50 in such manner that, when contactor F is energized, the latch is rotated in a counter-clockwise direction to a position in which the latch is out of engagement with the strip 34. The parts are so proportioned that when bimetallic strip 34 is undeflected, the pin 48 engages the lock rod 53 at the bottom of the slot 53^a, and holds the lock rod out of the notch 51^b in the latch 51; but that when strip 34 is deflected, the upper end of the rod enters the notch 51^b in latch 51, if contactor F is energized.

With the apparatus constructed in this manner, the operation of the apparatus when switch A is being moved from one extreme position to the other under normal conditions is the same as described in connection with Fig. 1. If the motor current rises above the normal value when switch A is being moved from its normal to its reverse position, however, the operation of the apparatus is as follows: When the motor current rises above the normal value, bimetallic strip 34 of relay T becomes deflected and opens contact 34-34^a of relay T, thereby de-energizing contactor E, and hence de-energizing motor M. When strip 34 becomes deflected, the end of the strip enters notch 51^a in latch 51 and is engaged by the latch so that the strip is subsequently held in its deflected position. If relay R is now energized in the reverse direction, to energize contactor F, latch 51 will be rotated out of engagement with strip 34. If strip 34 has cooled before this is done, the strip will immediately return to its normal position and close contact 34-34^a of relay T. If strip 34 is still heated, however, when latch 51 is rotated out of engagement with strip 34, the spring 55, acting through the arm 54, will cause the lock rod 53 to enter the notch 51^b. When the lock rod 53 enters the notch 51^b in the latch 51, it holds the

latch out of engagement with strip 34 until strip 34 cools even though contactor F becomes de-energized. When strip 34 cools, the pin 48 engages the rod 53 at the bottom of the slot 53^a and automatically pulls the lock rod 53 out of engagement with the latch, whereupon the latch returns to its normal position. When bimetallic strip 34 of relay T has returned to its normal position, contact 34-34^a of relay T becomes closed and the motor may then again be energized in the direction to move the switch from its normal to its reverse position by energizing relay R in the proper direction as will be readily understood from an inspection of the drawings.

If desired, relay S may also be provided with latching apparatus similar to that shown in Fig. 2 in connection with relay T.

One advantage of the apparatus shown in Fig. 2 over that shown in Fig. 1, is that when a thermal relay has operated due to excessive current in the motor circuit, it is unnecessary to wait until the bimetallic strip of the relay has cooled before reversing relay R to release the strip.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a movable device, a first and a second winding, a motor for driving said device, means effective when said first winding is energized for supplying said motor with current to operate said motor in one direction, a normally closed contact arranged to be opened if the current supplied to said motor exceeds a predetermined value when said first winding is energized, a latch effective when said contact is opened for subsequently holding said contact open, means for releasing said latch when said second winding is energized, and manually controlled means for at times energizing said first winding over said contact and for at other times energizing said second winding.

2. In combination, a device capable of assuming a first or a second position, a motor for operating said device, a first and a second winding, a first normally closed contact arranged to be opened if the current supplied to said motor exceeds a predetermined value when said first winding is energized, a second normally closed contact arranged to be opened if the current supplied to said motor exceeds a predetermined value when said second winding is energized, means effective when said first contact is opened for holding said first contact open until said second winding is subsequently energized, means effective when said second contact is opened for hold-

ing said second contact open until said first winding is subsequently energized, and manually controlled means for at times energizing said first winding over said first contact and for at other times energizing said second winding over said second contact.

3. In combination, a movable device, a first and a second winding, a motor for driving said device; a thermo-sensitive relay comprising a bimetallic strip which becomes deflected when heated, a heating element for heating said strip, and a contact controlled by said strip; means including said heating element for supplying said motor with current when said first winding is energized to operate said motor in one direction, means effective when said strip is deflected for subsequently holding said strip in its deflected position until said second winding is energized, and manually controlled means for at times energizing said first winding over said contact and for at other times energizing said second winding.

4. In combination, a device capable of assuming a first or a second position, an electric motor for operating said device, a first and a second winding; a first thermo-sensitive relay comprising a first heating element, a first bimetallic strip arranged to become deflected if said first heating element is supplied with current the magnitude of which exceeds a predetermined value, and a first contact which is opened when said first strip is deflected; a second thermo-sensitive relay comprising a second heating element, a second bimetallic strip arranged to become deflected if said second heating element is supplied with current the magnitude of which exceeds a predetermined value, and a second contact which is opened when said second strip is deflected; means effective when said first winding is energized and including said first heating element for supplying said motor with current to move said device from said first position to said second position, means effective when said second winding is energized and including said second heating element for supplying said motor with current to move said device from said second position to said first position, means effective when said first strip is deflected for holding said first strip in its deflected position until said second winding is energized, means effective when said second strip is deflected for holding said second strip in its deflected position until said first winding is energized, and manually controlled means for at times energizing said first winding over said first contact and for at other times energizing said second winding over said second contact.

5. In combination, a device capable of assuming a first or a second position, an electric motor for operating said device; a first contactor comprising a first winding, a first armature controlled by said first winding,

and a first and a second contact controlled by said first armature; a second contactor comprising a second winding, a second armature controlled by said second winding, and a 5 third and a fourth contact controlled by said second armature; means associated with said first and second armature for preventing either armature from moving to the position where its associated contacts are closed unless 10 the other armature occupies a position where its associated contacts are open, means controlled by said first and second contacts for supplying said motor with current to drive said device from said first position to said 15 second position, means controlled by said third and fourth contacts for supplying said motor with current to drive said device from said second position to said first position, a fifth normally closed contact arranged to be 20 opened if the current supplied to said motor exceeds a predetermined value when said first and second contacts are closed, a sixth normally closed contact arranged to be opened if the current supplied to said motor exceeds 25 a predetermined value when said third and fourth contacts are closed, and manually controlled means for at times energizing said first winding over said fifth contact and for at 30 other times energizing said second winding over said sixth contact.

6. In combination, a device capable of assuming a first or a second position, an electric motor for operating said device, a first and a second winding, a first thermo-sensitive relay comprising a first bimetallic strip which becomes deflected when heated, a first heating element for heating said first strip, and a first contact controlled by said first strip; a second thermo-sensitive relay comprising a second bimetallic strip which becomes deflected when heated, a second heating element for heating said second strip, and a second contact controlled by said second strip; means controlled by said first winding and including said first heating element for supplying said motor with current to drive said device from said first position to said second position, means controlled by said second winding and including said second heating element for supplying said motor with current to drive said device from said second position to said first position, means including said first contact for at times energizing said first winding, means including said second contact for at other times energizing said second winding, a first latch controlled by said second winding and biased to one position in such manner that said first latch will engage said first strip when said first strip becomes deflected and subsequently hold said first strip in its deflected position until said second winding is subsequently energized, and a second latch controlled by said first winding and biased to one position in such manner that said second latch

will engage said second strip when said second strip becomes deflected and subsequently hold said second strip in its deflected position until said first winding is subsequently energized.

7. In combination, a device capable of assuming a first or a second position, an electric motor operatively connected with said device, a first and a second winding, a first and a second heating element, means controlled by said first winding and including said first heating element for supplying said motor with current to drive said device from said first position to said second position, means controlled by said second winding and including said second heating element for supplying said motor with current to drive said device from said second position to said first position, a first bimetallic strip controlled by said first heating element in such manner that said first strip becomes deflected if said first heating element is supplied with current having a magnitude which exceeds a predetermined value, a second bimetallic strip controlled by said second heating element in such manner that said second strip becomes deflected if said second heating element is supplied with current having a magnitude which exceeds a predetermined value, a first contact controlled by said first bimetallic strip, a second contact controlled by said second bimetallic strip, means associated with said first strip and controlled by said second winding for at times holding said first strip in its deflected position, means associated with said second strip and controlled by said first winding for at other times holding said second strip in its deflected position, a circuit for said first winding including said first contact, and a circuit for said second winding including said second contact.

8. In combination, a device capable of assuming a first or a second position, an electric motor for operating said device, a first and a second winding; a thermo-sensitive relay comprising a bimetallic strip which becomes deflected when heated, a heating element for heating said strip, and a contact controlled by said strip; means controlled by said first winding and including said heating element for supplying said motor with current to drive said device from said first position to said second position, means controlled by said second winding for supplying said motor with current to drive said device from said second position to said first position, manually controlled means including said contact for at times energizing said first winding, manually controlled means for at other times energizing said second winding, a latch arranged to engage said strip when said strip becomes deflected to hold said strip in its deflected position, means controlled by said second winding for moving said latch

out of engagement with said strip, and means connected with said strip for holding said latch out of engagement with said strip until said strip cools if said latch is moved out of engagement with said strip when said strip is heated.

9. In combination, a railway switch having normal and reverse positions, an electric motor operatively connected with said switch, a first and a second winding, a first and a second heating element, means controlled by said first winding and including said first heating element for supplying said motor with current to drive said switch from its reverse position to its normal position, means controlled by said second winding and including said second heating element for supplying said motor with current to drive said switch from its normal position to its reverse position, a first bimetallic strip controlled by said first heating element in such manner that said first strip becomes deflected if said first heating element is supplied with current having a magnitude which exceeds a predetermined value, a second bimetallic strip controlled by said second heating element in such manner that said second strip becomes deflected if said second heating element is supplied with current having a magnitude which exceeds a predetermined value, a first contact controlled by said first bimetallic strip, a second contact controlled by said second bimetallic strip, a circuit controller controlled by said switch and having a fourth contact which is closed at all times except when said switch occupies its normal position and a fifth contact which is closed at all times except when said switch occupies its reverse position, a circuit for said first winding including said first contact and said fifth contact, a circuit for said second winding including said second contact and said fourth contact, a first latch controlled by said second winding and biased to one position in such manner that said first latch will engage said first strip when said first strip becomes deflected and subsequently hold said first strip in its deflected position until said second winding is energized, and a second latch controlled by said first winding and biased to one position in such manner that said second latch will engage said second strip when said strip becomes deflected and subsequently hold said second strip in its deflected position until said first winding is energized.

10. In combination, a railway switch having normal and reverse positions, an electric motor for operating said switch; a first contactor comprising a first winding, a first armature controlled by said first winding, and contacts controlled by said first armature; a second contactor comprising a second winding, a second armature controlled by said second winding, and contacts controlled by said

second armature; a first thermo-sensitive relay comprising a first bimetallic strip which becomes deflected when heated, a first heating element for heating said first strip, and a first contact controlled by said first strip; a second thermo-sensitive relay comprising a second bimetallic strip which becomes deflected when heated, a second element for heating said second strip, and a second contact controlled by said second strip; means controlled by the contacts of said first contactor and including said first heating element for supplying said motor with current to drive said switch from its normal position to its reverse position, means controlled by the contacts of said second contactor and including said second heating element for supplying said motor with current to drive said switch from its reverse position to its normal position, a circuit controller provided with a third contact which is closed at all times except when said switch occupies its extreme reverse position and with a fourth contact which is closed at all times except when said switch occupies its extreme normal position, a manually controlled polarized relay having a fifth contact which is closed when said polarized relay is energized by current of one relative polarity and a sixth contact which is closed when said polarized relay is energized by current of the other relative polarity a circuit for said first winding including said sixth contact, said first contact, and said third contact; a circuit for said second winding including said fifth contact, said second contact, and said fourth contact; a first latch controlled by said second armature and biased to one position in such manner that said first latch will engage said first strip when said first strip becomes deflected and subsequently hold said first strip in its deflected position until said second winding is energized; and a second latch controlled by said first armature and biased to one position in such manner that said second latch will engage said second strip when said second strip becomes deflected and subsequently hold said second strip in its deflected position until said first winding is energized.

11. In combination, a movable device, a first and a second winding, a motor for driving said device, means effective when said first winding is energized for supplying said motor with current to operate said motor in one direction, a normally closed contact arranged to be opened if the current supplied to said motor exceeds a predetermined value when said first winding is energized, means effective when said contact is opened for subsequently holding said contact open until said second winding is energized, and manually controlled means for at times energizing said first winding over said contact and

for at other times energizing said second winding.

12. In combination, a movable device, a first and a second winding, a motor for driving said device, means effective when said first winding is energized for supplying said motor with current to operate said motor in one direction, a normally closed contact arranged to be opened if the current supplied to said motor exceeds a predetermined value when said first winding is energized, mechanism effective when said contact is opened for subsequently holding said contact open, means operating upon the energization of said second winding to render said mechanism ineffective, and manually controlled means for at times energizing said first winding over said contact and for at other times energizing said second winding.

13. In combination, a movable device, a first and a second winding, a motor for driving said device, means effective when said first winding is energized for supplying said motor with current to operate said motor in one direction, a normally closed contact arranged to be opened if the motion of said device is arrested when said first winding is energized, means effective when said contact is opened for subsequently holding said contact open until said second winding is energized, and manually controlled means for at times energizing said first winding over said contact and for at other times energizing said second winding.

14. In combination, an electric motor, a winding, means controlled by said winding when said winding is energized for supplying said motor with current to operate said motor in one direction, governing means operating if the current supplied to said motor when said winding is energized exceeds a predetermined value for governing said winding, other means effective when said governing means has operated for subsequently retaining said governing means in the operated condition, and manually controlled means for at times energizing said winding and for at other times releasing said governing means from the operated condition.

15. In combination, an electric motor, a first and a second winding, means controlled by said first winding when and only when said first winding is energized for supplying said motor with current to operate said motor in one direction, other means operating if the current supplied to said motor when said first winding is energized exceeds a predetermined value for modifying the control of said means by said first winding, means effective when said other means has operated for subsequently retaining said other means in the operated condition until said second winding is energized, and manually controlled means for at times energizing said

first winding and for at other times energizing said second winding.

16. In combination, an electric motor, a first and a second winding, means controlled by said first winding when said first winding is energized for supplying said motor with current to operate said motor in one direction, a contact arranged to be operated if the current supplied to said motor exceeds a predetermined value when said first winding is energized for controlling said first winding, means effective when said contact has been operated for subsequently holding said contact in the operated position until said second winding is energized, and manually controlled means for at times energizing said first winding and for at other times energizing said second winding.

17. In combination, an electric motor, a first and a second winding, means controlled by said first winding when said first winding is energized for supplying said motor with current to operate said motor in one direction, a contact arranged to be operated if the current supplied to said motor exceeds a predetermined value when said first winding is energized for controlling said first winding, mechanism effective when said contact has been operated for subsequently holding said contact in the operated position, means operating upon the energization of said second winding to render said mechanism ineffective, and manually controlled means for at times energizing said first winding and for at other times energizing said second winding.

18. In combination, a movable device, a motor for driving said device, a first and a second winding, means controlled by said first winding when and only when said first winding is energized for supplying said motor with current to operate said motor in one direction, other means operating if the motion of said device is arrested when said first winding is energized for modifying the control of said means by said first winding, means effective when said other means has been operated for subsequently retaining said other means in the operated condition until said second winding is energized, and manually controlled means for at times energizing said first winding and for at other times energizing said second winding.

19. In combination, a movable device, a motor for driving said device, a first and a second winding, means controlled by said first winding when said first winding is energized for supplying said motor with current to operate said motor in one direction, a contact arranged to be operated if the motion of said device is arrested when said first winding is energized for controlling said first winding, means effective when said contact has been operated for subsequently holding said contact in the operated position until said second winding is energized, and manu-

ally controlled means for at times energizing said first winding and for at other times energizing said second winding.

20. In combination, an electric motor, a first and a second winding, a normal circuit controlled by said first winding for supplying said motor with current when and only when said first winding is energized, a reverse circuit controlled by said second winding for supplying said motor with current when and only when said second winding is energized, means associated with said first and second windings for preventing the supply of current to both said normal and said reverse circuits simultaneously, means associated with each of said normal and said reverse circuits and responsive to the magnitude of the current supplied to said motor for modifying the control of said normal and said reverse circuits by said first and said second windings respectively, and manually controlled means for at times energizing said first winding and for at other times energizing said second winding.

25. 21. In combination, an electric motor, a first and a second winding, a normal circuit controlled by said first winding for supplying said motor with current when and only when said first winding is energized, a reverse circuit controlled by said second winding for supplying said motor with current when and only when said second winding is energized, means associated with said first and second windings for preventing the supply of current to both said normal and said reverse circuits simultaneously, first and second means associated respectively with said normal and said reverse circuits for modifying the control of said normal and said reverse circuits by said first and said second windings and arranged to be operated when the current supplied to said motor exceeds a predetermined value, means effective when said first means has been operated for subsequently retaining said first means in the operated condition until said second winding is energized, means effective when said second means has been operated for subsequently retaining said second means in the operated condition until said first winding is energized, and manually controlled means for at times energizing said first winding and for at other times energizing said second winding.

22. In combination, an electric motor, a first and a second winding; a thermo-sensitive relay comprising a bimetallic strip which becomes deflected when heated, a heating element for heating said strip, and a contact controlled by said strip; means controlled by said first winding and including said heating element for supplying said motor with current to operate said motor in one direction when said first winding is energized, means controlled by said second winding for supplying said motor with current to

operate said motor in the other direction when said second winding is energized, manually controlled means for at times energizing said first winding over said contact and for at other times energizing said second winding, retaining means for holding said strip in the deflected position, means controlled by said second winding for releasing said strip from the deflected position, and means controlled by said strip for rendering said retaining means ineffective if said second winding is energized before said strip has become cooled.

23. In combination, a device capable of assuming a first or a second position, an electric motor for operating said device, a first and a second winding; a thermo-sensitive relay comprising a bimetallic strip and becomes deflected when heated, a heating element for heating said strip, and a contact controlled by said strip; means controlled by said first winding and including said heating element for supplying said motor with current to drive said device from said first position to said second position, means controlled by said second winding for supplying said motor with current to drive said device from said second position to said first position, manually controlled means including said contact for at times energizing said first winding, manually controlled means for at other times energizing said second winding, a latch provided with a first and a second notch and biased to one position in such manner that when said strip becomes heated said strip will be engaged by said latch at said first notch and held in its deflected position until said latch is moved out of engagement with said strip, means controlled by said second winding for moving said latch out of engagement with said strip, and a push rod biased to one position and pivotally attached to said strip in such manner that if said latch is moved out of engagement with said strip when said strip is deflected said rod will enter said second notch and hold said latch out of engagement with said strip until said strip cools.

24. In combination, a railway switch having normal and reverse positions, an electric motor operatively connected with said switch, a first and a second winding, a first and a second heating element, means controlled by said first winding and including said first heating element for supplying said motor with current in such manner that said motor moves said switch from its normal position to its reverse position, means controlled by said second winding and including said second heating element for supplying said motor with current in such manner that said motor moves said switch from its reverse position to its normal position, a first bimetallic strip controlled by said first heating element in such manner that said first strip becomes deflected if said first heating element is sup-

plied with current the magnitude of which exceeds a predetermined value, a second bimetallic strip controlled by said second heating element in such manner that said second strip becomes deflected if said second heating element is supplied with current the magnitude of which exceeds a predetermined value, a first contact controlled by said first bimetallic strip, a second contact controlled by said second bimetallic strip, a circuit controller controlled by said switch and having a third contact which is closed at all times except when said switch occupies its normal position and a fourth contact which is closed at all times except when said switch occupies its reverse position, a circuit for said first winding including said first contact and said fourth contact, a circuit for said second winding including said second contact and said third contact, a first latch associated with said first strip, a second latch associated with said second strip, means for causing said first latch to engage said first strip when said strip becomes deflected, means for causing said second latch to engage said second strip when said second strip becomes deflected, means controlled by said first winding for causing said second latch to be moved out of engagement with said second strip, means controlled by said second winding for causing said first latch to be moved out of engagement with said first strip, means controlled by said first strip for holding said first latch out of engagement with said first strip until said strip returns to its normal position if said latch is moved out of engagement with the strip when the strip is deflected, and means controlled by said second strip for holding said second latch out of engagement with said second strip until said second strip returns to its normal position if said second latch is moved out of engagement with the strip when the strip is deflected.

In testimony whereof I affix my signature.
45 BERNARD E. O'HAGAN.
